(57) **CLAIM**

I claim the ornamental design for a double compartment aluminum food pan, as shown and described.

DESCRIPTION

FIG. 1 is an exploded perspective view of the double compartment aluminum food pan embodying the design of the present invention, shown with the top removed for completeness of illustration.

FIG. 2 is a top plan view thereof.

FIG. 3 is a bottom view thereof.

FIG. 4 is an end elevational view thereof, the end opposite to the end shown in FIG. 4 being identical to the end shown in FIG. 4; and,

FIG. 5 is an side elevational view thereof, the side opposite to the side shown in FIG. 5 being identical to the side shown in FIG. 5.
